UNITED STATES PATENT OFFICE

106,513

DESIGN FOR A DRESS

Vivian Amen, New York, N. Y.

Application September 2, 1937, Serial No. 71,422

Term of patent 3½ years

To all whom it may concern:

Be it known that I, Vivian Amen, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The floral units on the blouse section of the dress are comprised of sequins.

I claim:

The ornamental design for a dress, substantially as shown, and described.

VIVIAN AMEN.
